CHRISTIAN CUSTER, OF PHILADELPHIA, PENNSYLVANIA, ASSIGNOR TO
HIMSELF AND CHARLES K. BULLOCK, OF SAME PLACE.

Letters Patent No. 79,211, dated June 23, 1868.

IMPROVED FLOUR-PACKER.

The Schedule referred to in these Letters Patent and making part of the same.

TO ALL WHOM IT MAY CONCERN:

Be it known that I, CHRISTIAN CUSTER, of Philadelphia, Pennsylvania, have invented an Improved Flour-Packing Machine; and I do hereby declare the following to be a full, clear, and exact description of the same.

My invention consists of certain mechanism, fully described, for packing flour, &c., in barrels, the mechanism being such that it accomplishes its duty effectually and rapidly.

In order to enable others skilled in the art to make and use my invention, I will now proceed to describe its construction and operation, reference being had to the accompanying drawing, which forms a part of this specification, and in which—

Figure 1, Drawing No. 1, is an edge view of my machine for packing flour, &c., in barrels.

Figure 2, Drawing No. 1, a plan view of fig. 1.

Figure 3, Drawing No. 2, a vertical section on the line 1-2, fig. 1.

Figure 4, a front view of the machine.

Figure 5, a vertical section of part of the machine drawn to an enlarged scale; and

Figures 6, 7, and 8, detached views of part of the machine.

Similar letters refer to similar parts throughout the several views.

A is the base of the machine, to which are secured two standards, B and B', the latter being connected together at the top by a hopper, C, and frame, D, referred to hereafter.

Through the base, A, passes a rod, a, surmounted with a platform, b, on which the barrel E to be packed rests, the lower end of the bar being connected to one arm of a lever, F, which is hung beneath the base, A, and to the other arm of which is jointed a rod, c, projecting through the base, A, and having a shoulder, c', for catching beneath the said base, as seen in fig. 3.

To the hopper C is secured a hollow cylinder, G, and on the latter another hollow cylinder, H, is arranged to slide freely, but is prevented from turning by rods, d d, projecting into guides in the uprights B and B', (see fig. 3.)

In a cross-bar, e, within the cylinder G, turns a vertical shaft, I, which also turns in a cross-bar, e', in the cylinder H, and this shaft is provided with two screw-propellers, f and f', one on each side of the said cross-bar e'.

It should be here noted that the thread of the upper screw-propeller is made of a coarser pitch than that of the lower propeller, and that the cross-bar e' is not straight, but bevelled or inclined, as shown in figs. 6, 7, and 8.

The shaft I passes through and is arranged to slide in the hub of a bevel-wheel, J, the latter having a pin or key entering a groove in the shaft, so that the latter cannot turn without the wheel.

To the frame D, above referred to, is secured a plate, K, fig. 5, which has a tubular projection, h, surrounding but not in contact with the shaft I. The plate has also an annular projection, h', between which and the tube h projects the annular flange g on the under side of the wheel J. There is a rim, t, round the edge of the plate K, so as to form a recess, m, for catching such oil as may drop from the bearing.

The wheel J rests on the annular projection h', and in the space n, between the latter and the tubular projection h, is deposited oil, or other lubricating-material.

Into the bevel-wheel J gears a pinion, J', on a shaft, L, which turns in suitable bearings on the frame D, and which is provided with a fast pulley, M, and loose pulley, M'.

A horizontal bar, N, is arranged to slide in projections p p on the frame D, this bar having an opening, p', through which the strap for driving the pulleys passes.

The lower end of a vertical rod, q, is secured to the sliding cylinder H, and this rod is provided with two adjustable stops, q' and q'', which, under the circumstances described hereafter, come in contact with and operate an arm, t, hinged to the strap-bar N.

This arm t is so connected to a weighted lever, P, hung to a pin on the frame D, that, by the aid of the

said lever, the driving-strap will be moved to the fast pulley M when the stop q'' comes in contact with the arm t , and will be moved to the loose pulley when the stop q' comes in contact with the said arm.

A horizontal shaft, Q, is arranged to turn in suitable bearings on the standard B', and on this shaft is a ratchet-wheel, R, to the teeth of which is adapted a pawl, R', hung loosely to the said standard.

There are also on the shaft Q two barrels, S and S', round each of which is several times coiled a rope or chain, T, to one end of which is attached a weight, V. One of these ropes or chains is attached at x to the sliding cylinder H at one side of the same, and the other rope to the same cylinder on the opposite side.

Operation.

The sliding cylinder H, having been lowered to the position seen in fig. 3, and an empty barrel having been placed on the platform b, and elevated by the depression of the bar c, the shaft I with its propellers is caused to revolve, while the flour enters the hopper C at the two points indicated by the arrows in that figure.

The propeller f, with the coarse thread, collects the loose flour which falls into the tube H, and forces it past the cross-bar e', the arms of which are so inclined as to present no impediment to the free passage of the flour to the propeller f', the finer thread of which compresses the flour and packs it tightly into the barrel.

As the packing continues, the cylinder H, with its shaft I and propellers, rises, and continues to rise, until the barrel is packed with flour, when the stop q' comes in contact with the arm t , and the driving-strap is moved from the fast pulley M to the loose pulley M', and the movement of the shaft and its propellers is discontinued.

The pawl R', which, during the descent of the sliding cylinder, had been raised free from contact with the ratchet-wheel, is now depressed, so as to prevent the shaft Q from turning, and the cylinder from descending.

The platform b, with its packed barrel, is now, by operating the rod e, permitted to fall to the base by its own weight, and is removed to make way for an empty barrel, which is elevated as before to the position shown in fig. 3.

The operator now seizes the hand-wheel y on the shaft Q, and, after raising the pawl R' free from contact with the ratchet-wheel, permits the cylinder and its propellers to fall by its own weight, at the same time maintaining such a hold of the wheel as to prevent the sudden falling of the said cylinder.

When the latter has been lowered to the desired point, the stop q'' of the rod q comes in contact with the arm t , and the strap is moved thereby from the loose pulley M' to the fast pulley M, the shaft I with its propellers consequently set in motion, and the packing of the barrel proceeded with as before.

I claim as my invention, and desire to secure by Letters Patent—

1. The combination, in a flour-packing machine, of a stationary cylinder, G, with a sliding cylinder, H, within which operate the devices for propelling and packing the flour.

2. The within-described propelling-device, consisting of two propellers, f and f', attached to a shaft, I, one on each side of a cross-bar, e', having inclined arms, the whole being combined with the sliding cylinder H, substantially as specified.

3. The sliding cylinder H and strap-bar, N, so connected that the said bar will be operated by the movement of the cylinder, substantially as described.

In testimony whereof, I have signed my name to this specification in the presence of two subscribing witnesses.

CHRISTIAN CUSTER.
